J. E. KENKEL

ADVERTISING DEVICE FOR DISPENSING MACHINES

Filed Feb. 3, 1927

Patented Oct. 16, 1928.

1,688,278

UNITED STATES PATENT OFFICE.

JOHN EDWIN KENKEL, OF GREAT FALLS, MONTANA.

ADVERTISING DEVICE FOR DISPENSING MACHINES.

Application filed February 3, 1927. Serial No. 165,639

This invention relates to an advertising device which operates in conjunction with a dispensing machine for displaying advertisements, and including means for attracting 5 attention to the advertisements.

The principal object of the present invention is to incorporate in a dispensing machine, a device which embodies means for carrying advertising matter, and means for 10 attracting attention to the advertising matter which is operable in response to the operation of a manipulator forming a part of the machine.

With the foregoing, other objects of the 15 invention will appear from the embodiment of the invention which by way of example is described in the following specification and illustrated in the accompanying drawings, in which—

20 Figure 1 is a sectional elevation showing the device of the present invention incorporated in a dispensing machine of a known type.

25 Fig. 2 is a sectional view taken on the line 2—2 of Fig. 1.

Fig. 3 is a sectional view taken on the line 3—3 of Fig. 2.

Fig. 4 is an elevation of the main part of the device.

30 As before stated, the present invention resides in providing a device which operates in conjunction with a dispensing machine for displaying advertisements, and which includes means for attracting attention to the 35 advertisements. In the present instance, the device of the present invention is incorporated in a dispensing machine, the construction and operation of which is fully disclosed in Letters Patent of the United States,

40 No. 1,600,886, granted to me September 21, 1926. The machine is indicated at 10 in Fig. 1. The machine is designed for dispensing toothpicks. The machine includes a pivotally mounted toothpick delivery member 11, and for a full understanding of the 45 operation of the device of the present invention, it is only necessary to deal with the member 11. The said member 11 is in the form of a manipulator, and has a trough 12 formed on its inner end, which is pivoted as at 13 near the trough end, so that the manipulating end 14 will be disposed normally in a lowered position. By raising the 50 manipulating end 14 of the member 11, a toothpick is delivered to a position from

which it may be readily removed, in virtue of the coaction of other parts of the machine with the member 11. The device of the present invention operates in conjunction with the member 11. In the present instance the 60 device includes a main unitary assemblage 15 which is positioned at the rear of the machine, as shown most clearly in Fig. 1. The assemblage 15 includes a casing-like structure 16 having a front panel or plate 17 on the front face portions 18 and 19 of which any preferred advertisements may be placed. The said plate 17 has an opening 20 therein. The structure 16 has a rear wall 21 which extends below the plate 17, is 70 spaced therefrom, and is disposed substantially parallel thereto. In order to attract attention to the advertising matter of the plate 17 there is provided some suitable object or element 22, which may be of any design. The said object or element 22 is arranged on the upper end of a member 23 of spring metal. The lower end of the member 23 is secured in any preferred manner to the lower end of the rear wall 21. In the 75 present instance the lower end of the member 23 is fastened between two small lugs 24 on a fixture 25 secured to or formed on the wall 21. The member 23 being of spring metal is adapted to be flexed by a force applied thereto, and when the force is withdrawn, the said member 23 reacts and vibration thereof ensues, therefore causing the element 22 to move alternately in opposite directions. The element 22 is disposed adjacent the opening 20 and will therefore be 80 visible. The movement of the element 22 will attract the attention of a person who will be led to read the advertisements appearing on the plate 17. 85

90 In order to accomplish the flexing of the member 23, means is arranged between the member 23 and the member 11 hereinbefore referred to. The said means, in the present instance, includes a pendulum 26 carried by 95 the rear wall 21. The said pendulum 26 has a lateral portion 27, and a portion 28 which is disposed substantially at a right angle with respect to the plane of the pendulum, and is also disposed on an angle with 100 respect to a horizontal plane. The said portion 28 functions as a cam. A pin 29 on the portion 28 is adapted to act on the member 23 for the flexing operation. A lever 30 105 is provided. One end of the lever 30 coacts 110

with the cam portion 28, and the opposite end of the lever 30 is acted on by the trough 12 of the member 11 when the latter is raised in the toothpick dispensing operation. The 5 end of the lever 30 which coacts with the cam portion 28 has limited downward movement. A screw 31 adjustable in a lug 32 carried by the wall 21 limits the downward movement of the end of the lever 30 which 10 coacts with said cam portion 28. The said end of the lever 30 is heavier than the opposite end, and therefore has a normal tendency to rest on the screw 31.

From the foregoing it will be understood, 15 that when the member 11 is manipulated by pulling upwardly on the end 14, the trough 11 will bear down on the related end of the lever 30. As a consequence the opposite end of the lever 30 will coact with 20 the cam portion 28, causing the pendulum 26 to move toward the member 23, and as a result, the pin 29 will bear on the member 23 causing the latter to flex to a position indicated in dotted lines in Fig. 4. When 25 the member 11 is released, it will drop to its normal position, shown in full lines in Fig. 1, the lever 30 will also move to its normal position, shown in Fig. 1, the pendulum 26 will swing to its normal position 30 shown in full lines in Fig. 4. When these parts have returned to their normal positions, the member 23 will spring back and continue to vibrate thereby causing the object 22 to move alternately in opposite directions. 35 Each time the delivery member 11 is manipulated, the object 22 will be caused to move in a similar manner, therefore always attracting a persons attention to the advertising matter appearing on the face portions of the plate 17. The value of the dispensing machine to which the device of 40 the present invention is attached, will be enhanced, as it will serve not only for dispensing the goods within the same but will 45 also serve as an advertising medium.

It is to be understood that the invention is not restricted to the precise arrangement of parts shown and described, as details of construction may be modified and rearranged without departing from the spirit of the invention, the scope of which is limited only by the terms of the appended claims. 50

I claim:

1. An advertising device comprising a casing 55 having a face for advertising matter,

a flexible member secured at one end to said casing, and object at the free end of the flexible member adjacent said face, said object movable with the flexible member when the latter is flexed, to attract attention 60 to said face, the object being moved alternately in opposite directions when the flexible member is flexed, and means for flexing said flexible member.

2. The combination with a dispensing machine including a manipulator; of a casing having a face for advertising matter, an element arranged adjacent said face to be freely oscillated to attract attention thereto; and means between said manipulator and element 65 causing the oscillation of said element in response to the manipulation of the manipulator.

3. The combination with a dispensing machine including a lever; of a casing having a face for advertising matter, an element arranged adjacent said face to be freely oscillated to attract attention thereto, and means between said lever and element causing the oscillation of said element in response to the manipulation of the lever. 75

4. The combination with a dispensing machine including a manipulator; of a plate adapted to carry an advertisement, a flexible member fixed at one end having an object 80 on its free end, said object being movable with the flexible member when the latter is flexed to attract attention to said plate, said object being movable adjacent an opening 85 in said plate, and means between the manipulator and the flexible member causing the flexible member to flex in response to the manipulation of the manipulator, said flexible member being adapted to react in consequence of the initial flexing to cause the object carried by the flexible member to move 90 alternately in opposite directions. 95

5. The combination with a dispensing machine, of a plate having an opening, a member fixed at one end and adapted to vibrate 100 and having an object thereon, said object disposed adjacent the opening in the plate adapted to carry advertising matter, and means including a delivery member of the machine operable to cause the vibration of 105 said member to cause the object carried thereby to move alternately in opposite directions.

JOHN EDWIN KENKEL.
